[57] **CLAIM**

The ornamental design for a flashlight, as shown and described.

DESCRIPTION

FIG. 1 is an environmental left elevational view of a flashlight showing my new design;

FIG. 2 is a right elevational view thereof;

FIG. 3 is a top plan view thereof;

FIG. 4 is a bottom plan view thereof;

FIG. 5 is a front elevational view, shown on an enlarged scale to show detail, thereof; and,

FIG. 6 is a rear elevational view, shown on an enlarged scale to show detail, thereof.

The broken line showing of the clip and key ring in FIGS.

1-6 is for illustrative purposes, showing the types of clips and keyrings that can be used, and forms no part of the claimed design.
